Primary Examiner — Karen S Acker(74) Attorney, Agent, or Firm — Lewis Roca Rothgerber Christie LLP(57) CLAIM

The ornamental design for office chair, as shown and described.

DESCRIPTION

FIG. 1 is a perspective view of the office chair;

FIG. 2 is a front view thereof;

FIG. 3 is a first side view thereof;

FIG. 4 is a back view thereof;

FIG. 5 is a second side view thereof; and,

FIG. 6 is a top view thereof.

The broken lines depict portions of the office chair that form no part of the claimed design.
